UNITED STATES PATENT OFFICE

ION VON KERT HOTT, OF DAYTON, OHIO, ASSIGNOR TO THE JOYCE-CRIDLAND COMPANY,
OF DAYTON, OHIO, A CORPORATION OF OHIO

LIFTING DEVICE

Application filed January 3, 1927. Serial No. 158,629.

This invention relates to lifting devices and more particularly to a pawl and ratchet jack of the type shown in the application for patent filed by Hott and Spear on February 2, 1925, Serial No. 6,318. The jack there shown comprises a toothed element with which cooperates a lifting pawl and a detent pawl. Loosely connected with both pawls is a rod, and springs carried by this rod act on the pawls to control their positions with relation to the toothed element.

The object of the present invention is to provide in such a jack means whereby both pawls may be moved to their inoperative positions to permit the lifting element to move quickly to its lowermost position.

A further object of the invention is to provide such a device which will be very simple in its construction and operation and which will be of such a character and so arranged that it will not in any way interfere with the operation or handling of the jack.

Other objects of the invention will appear as the device is described in detail.

In the accompanying drawings Fig. 1 is a side elevation, partly broken away, of a lifting jack embodying my invention; Fig. 2 is a vertical sectional view of such a jack, partly broken away; Fig. 3 is a side elevation of the upper portion of the jack, partly broken away to show the lifting pawl in its elevated position; and Fig. 4 is a similar view showing the tripping device in its operative position.

In these drawings I have illustrated one embodiment of my invention and have shown the same as comprising a base 1 on which is mounted a vertical standard 2 having a guide-way in which is slidably mounted a toothed element 3. In the present instance, I have shown the invention as applied to a pole jack and the upper end of the lifting element is claw shaped, as is customary in such jacks, and the standard 2 is pivotally mounted at 4 on the base and is held normally in its upright position by means of a latch 5 having an actuating arm 6.

Pivotally mounted on the standard 2, in front of the toothed element 3, is a pawl carrier which is here shown as comprising a trunnion 7 having an enlarged portion 8 and

provided with means for actuating the same, such as a lever socket 9 to receive the usual operating bar or lever. A lifting pawl 10 is pivotally mounted on the pawl carrier at 11, the point of connection of the pawl with the pawl carrier, or enlarged portion of the trunnion, being spaced some distance from the axis of the trunnion so that the movement of the latter will impart bodily movement to the pawl. This pawl has secured thereto and preferably formed integral therewith an apertured lug 12 which extends rearwardly and laterally therefrom. Pivotally mounted on the standard 2 above the trunnion 7 is a detent pawl 13 which is also provided with a rearwardly and laterally extending apertured lug 14. The lugs 12 and 14 are arranged with their apertures in alinement and a rod 15 is slidably mounted in said apertures. This rod has at its upper and lower ends stops 16 and 17 and at a point between its ends it is provided with a stop 18. The stop 17 is located below and adapted to engage the apertured lug 12 of the lifting pawl and the intermediate stop 18 is located below and adapted to engage the apertured lug 14 of the detent pawl. A spring 19 is confined between the apertured lug 12 of the lifting pawl and the intermediate stop 18 and a spring 20 is confined between the apertured lug 14 of the detent pawl and the upper stop 16. Means are provided for depressing the rod 15 and holding the same in a depressed position during the lifting operation and this means is here shown as comprising a pivoted plate 21 adapted to engage the upper end of the rod 15 and this plate is actuated by a finger 22 connected with a pivoted operating handle 23. When the rod is held in its depressed position the springs 19 and 20 will be under compression and will tend to hold the pawls in engagement with the toothed element. When the pawl carrier is operated to impart upward movement to the lifting pawl the lifting element will be moved upwardly, the detent pawl yielding to permit the teeth of the toothed element to ride past the same, and when the pawl carrier is moved downwardly the detent pawl will hold the toothed element against downward movement and the lifting

pawl will yield and ride over the teeth of the toothed element, thus permitting the load to be elevated step by step. When it is desired to lower the load the locking plate 21 is released and the springs will move the rod into the position shown in Fig. 1. As there shown, the detent pawl is in engagement with the toothed element and the lifting pawl has been moved out of engagement therewith by the contact of the lower stop 17 with the apertured lug 12. When the pawl carrier is actuated to move the lifting pawl upwardly, this pawl will move relatively to the toothed element but as it moves upwardly the spring 19 will be placed under compression and will rock the pawl about its individual axis 11 to cause the nose thereof to engage the toothed element, the rod tilting to permit of the movement of the pawl. The movement is so timed that the lifting pawl will engage the toothed element just before the pawl completes its upward movement and the final movement of the pawl will impart a slight upward movement to the toothed element, thereby releasing the detent pawl and permitting the same to be moved to its inoperative position by the action of the spring 19 and stop 18 on the lug 14 of the detent pawl. The load is then carried by the lifting pawl and as the pressure on the operating handle is relieved the load will move downwardly. As the toothed element and lifting pawl move downwardly the lug 12 of the lifting pawl will engage the lower stop 17 on the rod and cause the rod to move downwardly, thereby causing the detent pawl to be moved toward the lifting element. This movement is so timed that the detent pawl will not engage the lifting element until one or more teeth of the toothed element have passed the pawl but it will engage the lifting element and support the load just before the lifting pawl reaches its lowermost position. The final downward movement of the lifting pawl will cause the lug 12 thereon to engage the lower stop 17 which will rock the pawl about its axis and move it out of engagement with the toothed element. By repetition of this cycle of operations the load may be lowered step by step.

The mechanism and operation above described enable the load to be raised and lowered step by step but it is sometimes desirable to lower the load quickly, that is, to permit the lifting element to move quickly to its lowermost position. To accomplish this I have provided means whereby said pawls may be moved to their inoperative positions, thereby releasing the toothed element and permitting of the free downward movement thereof, either with or without load. In the present construction, the standard 2 has formed therein a vertical guideway 24 in which is slidably mounted a tripping member 25, which is here shown in the form of a bar or plunger, the upper end of which is arranged in line with

and adapted to engage the lower end of the rod 15. Preferably the upper end of the tripping plunger has an enlarged head 26 to provide it with sufficient area to contact with the end of the rod when the latter is in either its true vertical position or its tilted position. The lower end of the plunger has a laterally extending portion or foot 27 which is adapted to be engaged by an actuating cam 28 pivotally mounted at 29 on the standard 2. Connected with the cam is an operating member, here shown in the form of a handle 30 and so arranged that when the cam is in its inoperative position the handle will extend alongside of the standard and close thereto. The cam 28 is so shaped that when the handle is moved outwardly and upwardly the cam will force the plunger upwardly and thus cause it to contact with the rod 15 and move that rod upwardly. The nose 31 of the cam is so arranged that when the cam is in its uppermost or fully operative position the point of contact between the plunger and the cam will be offset or arranged on the outer side of the axis of the cam so that when the cam is released the pressure of the plunger thereon will restore the cam to its inoperative position, thereby preventing the cam from being inadvertently left in a position which would render the mechanism inoperative.

When the locking plate 21 is released and the operating lever 9 is in its lowermost position the lifting pawl will be in engagement with the toothed element and the detent pawl will be in its inoperative position. If the lifting pawl has sufficient movement with relation to the pawl supporting member 8 the rod 15 may be moved far enough to force this pawl out of engagement with the toothed element, but where, as in the present instance, the movement of the pawl is limited the upward movement of the rod will not force the pawl to its inoperative position but the tripping member 25 will hold the rod in its elevated position so that the downward movement of the pawl, when the operating lever is elevated, will cause the lug 12 on the lifting pawl to engage the lower stop 17 on the rod, thus rocking the pawl about its axis to an inoperative position and releasing the toothed element.

When the operating lever is in its raised position the lifting pawl will be in its inoperative position and the detent pawl in its operative position, and the upward movement imparted to the rod by the tripping device will force the detent pawl out of engagement with the toothed element.

The actuating device for the plunger may be of any suitable character but, in the present instance, I have utilized for this purpose one of two carrying handles 30 which are pivotally mounted on the opposite sides of the standard 2 and are provided with surfaces 32 arranged to contact with the sides of the

standard and form stops to limit the upward movement of the handles. One of the carrying handles is arranged beneath the plunger 25 and in order to utilize the same as an actuating device for the plunger I have shaped the upper end thereof, beyond the surface 32, to provide the cam 28, which will engage and actuate the plunger when the handle is moved to its extended position.

10 While I have shown and described one embodiment of my invention I wish it to be understood that I do not desire to be limited to the details thereof as various modifications may occur to a person skilled in the art.

15 Having now fully described my invention, what I claim as new and desire to secure by Letters Patent, is:

1. In a lifting device, a standard, a toothed element carried by said standard, a lifting pawl and a detent pawl supported on said standard and cooperating with said toothed element, means to actuate said lifting pawl, a rod connected with and capable of longitudinal movement with relation to said 25 pawls, springs carried by said rod and acting on said pawls, means to control the longitudinal movement of said rod and thereby control the operation of said pawls, and other means to control the longitudinal movement of said rod to cause both of said 30 pawls to assume inoperative positions with relation to said toothed element.

2. In a lifting device, a standard, a toothed element carried by said standard, a lifting pawl and a detent pawl cooperating with said toothed element, means to actuate said lifting pawl, a rod connected with and capable of longitudinal movement with relation to said pawls, springs carried by said 40 rod and acting on said pawls, means to control the longitudinal movement of said rod and thereby control the operations of said pawls, a tripping device to act on said rod to cause said pawls to be moved into inoperative 45 positions, and means for actuating said tripping device.

3. In a lifting device, a standard, a toothed element carried by said standard, a lifting pawl and a detent pawl cooperating with said toothed element, means to actuate said lifting pawl, a rod connected with and capable of longitudinal movement with relation to said pawls, springs carried by said 50 rod and acting on said pawls, a tripping device slidably mounted on said standard and arranged to engage said rod, and means for imparting sliding movement to said tripping device.

4. In a lifting device, a standard, a toothed element carried by said standard, a lifting pawl and a detent pawl cooperating with said toothed element, means to actuate said lifting pawl, a rod connected with and capable of longitudinal movement with relation to said pawls, springs carried by said 55

rod and acting on said pawls, a tripping device slidably mounted on said standard and arranged to engage said rod, a cam acting on said tripping device to impart sliding movement thereto, and means for actuating said cam.

5. In a lifting device, a standard, a toothed element carried by said standard, a lifting pawl and a detent pawl cooperating with said toothed element, means to actuate said lifting pawl, a rod connected with and capable of longitudinal movement with relation to said pawls, springs carried by said 70 rod and acting on said pawls, a plunger slidably mounted on said standard, a cam pivotally mounted on said standard beneath said plunger and having a contact portion offset from the axle thereof, and a handle operatively connected with said cam.

6. In a lifting device, a standard, a toothed element carried by said standard, a lifting pawl and a detent pawl cooperating with said toothed element, means to actuate said lifting pawl, a rod connected with and capable of longitudinal movement with relation to said pawls, springs carried by said rod and acting on said pawls, means for moving said rod in one direction to cause both pawls to be moved into operative relation to said toothed element, and means for moving said rod in the opposite direction to permit both pawls to be moved into inoperative 90 positions with relation to said toothed element.

7. In a lifting device, a standard, a toothed element carried by said standard, a lifting pawl and a detent pawl supported on said standard and cooperating with said toothed element, means for actuating said lifting pawl, and means for controlling the positions of said pawls with relation to said toothed element, said means comprising springs acting on said pawls, a rod having longitudinal movement with relation to both pawls, means to limit the movement of said rod in one direction to cause both pawls to be operatively engage said toothed element, and means movable into and out of a position to limit the movement of said rod in the other direction and thus cause both pawls to be moved into inoperative positions with relation to said toothed element.

In testimony whereof, I affix my signature hereto.

ION VON KERT HOTT.
